United States Patent Office

Des. 184,460
Patented Feb. 17, 1959

184,460

FISH LURE

Frank A. Serafin, Oakland County, Mich., assignor of one-half to Solomon Newhouse, Pontiac, Mich.

Application December 23, 1957, Serial No. 48,986

Term of patent 14 years

(Cl. D31—4)

Fig. 1 is a top plan view of a fish lure showing my new design;

Fig. 2 is a side elevational view thereof;

Fig. 3 is a bottom plan view of Fig. 2; and

Fig. 4 is an end elevational view taken from the right of Fig. 2.

The broken line shown is for illustrative purposes only.

I claim:

The ornamental design for a fish lure, as shown and described.
